Primary Examiner—Carol Rademaker(74) *Attorney, Agent, or Firm*—Banner & Witcoff, Ltd.(57) **CLAIM**

The ornamental design for a portion of a bottle, as shown and described.

DESCRIPTION

FIG. 1 is a perspective view of a bottle depicting the new design;

FIG. 2 is a front elevation plan view of the bottle depicted in FIG. 1;

FIG. 3 is a side elevation plan view of the bottle depicted in FIG. 1;

FIG. 4 is a top plan view of the bottle depicted in FIG. 1; and, FIG. 5 is a bottom plan view of the bottle depicted in FIG. 1. The dash lines shown in the drawings are for illustrative purposes only and form no part of the claimed design. The dot-dash-dot lines shown in the drawings define the boundary of the claim and form no part of the claimed design.
